UNITED STATES PATENT OFFICE

109,270

DESIGN FOR A TEXTILE FABRIC

Mac Etlinger, New York, N. Y.

Application February 19, 1938, Serial No. 75,269

Term of patent 3½ years

To all whom it may concern:

Be it known that I, Mac Etlinger, a citizen of the United States of America, residing in the city of New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design. The dot and dash lines on the drawing show the design unit, which unit is repeated in staggered relation, as indicated by the angles A and A'.

I claim:

The ornamental design for a textile fabric substantially as shown and described.

MAC ETLINGER.
